GEORG STERN,
BY ALBERT S. DANI
HIS ATTORNEY.

UNITED STATES PATENT OFFICE.

GEORG STERN, OF BERLIN, GERMANY, ASSIGNOR TO GENERAL ELECTRIC COMPANY, A CORPORATION OF NEW YORK.

OIL-SWITCH.

1,171,272.

Specification of Letters Patent.

Patented Feb. 8, 1916.

Application filed July 21, 1913. Serial No. 780,102.

To all whom it may concern:

Be it known that I, GEORG STERN, a subject of the King of Prussia, residing at Berlin, Germany, have invented certain new 5 and useful Improvements in Oil-Switches, of which the following is a specification.

My invention relates to devices for interrupting circuits in oil, and more particularly to oil switches and similar devices.

10 When circuits carrying large amounts of energy are interrupted by means of contacts which separate under oil, a decomposition of the oil is caused by the arc and the products of decomposition form an explosive mixture with the air above the oil level. This explosive mixture may easily be ignited by a glowing spark coming from the contacts and therefore may cause the destruction of the apparatus and endanger the 15 surroundings. An attempt has been made to meet this difficulty by tightly closing the oil receptacle of the oil switch so as to leave no air at all in the oil switch itself. Pressure equalization and the escape of the arc 20 gases were provided for by means of a stand pipe filled with oil. As tests have shown, this arrangement has the disadvantage that the high pressures generated in the oil switch during the interruption of circuits 25 carrying a large amount of energy cannot be controlled and are apt to cause the destruction of the oil vessel.

The object of the present invention is to minimize the danger due to the presence of 30 an explosive mixture above the oil. To this end the present invention does not attempt to prevent entirely the formation of the explosive mixture previously referred to, but confines any explosion that may occur to a 35 relatively small space. In the preferred construction this result is attained by a special formation of the cover of the oil vessel.

40 The invention will best be understood in connection with the accompanying drawing in which merely for purposes of illustration I have shown one of the many forms in which the invention may be embodied, and in which—

45 Figure 1 is a bottom plan view of the cover of an oil vessel embodying my invention; and Fig. 2 is a longitudinal section of an oil switch with a top or cover such as shown in Fig. 1.

50 In the particular form of device shown in the drawings by way of example, the oil

vessel *a* is provided with a cover *b* which has a number of ribs *c* projecting downwardly into the oil *d* in the oil vessel. As a result of this construction the air cushion *e* above the oil is divided by the ribs *c* into 60 a number of pockets or chambers which are closed at the upper end and are not in communication, although all of them are open to the oil *d* which seals the lower ends. As clearly appears from the drawing, the cover 65 is provided with a large number of perpendicular ribs on the inner side, which are of such dimensions that they extend a little below the oil level when the oil switch is assembled. The number of ribs should be so 70 selected that the air spaces or pockets are relatively small as compared to the entire amount of air between the oil level and the cover. It is immaterial whether the ribs cross each other, as shown in Fig. 1, or run 75 in only one direction, or whether the cast metal body of the cover is so constructed in some other way that quite a large number of separate air chambers or pockets are formed above the oil. Care should be taken 80 that in some suitable way the air can, if necessary, easily be removed from the air pockets.

What I claim as new and desire to secure by Letters Patent of the United States, is,— 85

1. In a circuit-interrupting device, the combination of a vessel partially filled with oil, means for interrupting the circuit in said vessel beneath the oil, and means for dividing only the space above the oil into a 90 plurality of non-communicating chambers open at the lower end only.

2. A circuit-interrupting device comprising a vessel partially filled with oil, circuit terminals extending into said vessel to a 95 point beneath the surface of the oil, and partitions extending through the space above the oil to divide only said space into a plurality of non-communicating pockets open at the lower end only and with their 100 lower ends beneath the surface of the oil in said vessel.

3. An oil switch comprising a vessel partially filled with oil, relatively movable co-operating contacts mounted to separate in said vessel beneath the oil, a cover for said vessel, and means co-operating with said cover to form a plurality of pockets open only to the oil in said vessel. 105

4. An oil switch comprising a vessel par- 110

tially filled with oil, relatively movable co-operating contacts mounted to separate in said vessel beneath the oil, and a cover for said vessel provided with a plurality of ribs 5 extending downwardly into the oil to form a plurality of separate chambers open only to the oil.

5. An oil switch comprising a vessel containing oil and having an air cushion above 10 the oil, relatively movable co-operating contacts mounted to separate in said vessel beneath the oil, and a cover for said vessel

having a plurality of ribs extending downwardly from said cover to below the oil level to divide the air cushion into a plurality of 15 separate air chambers and thereby restrict any ignition of explosive gases which may occur in said chambers.

In witness whereof, I have hereunto set my hand this 7th day of July, 1913.

GEORG STERN.

Witnesses:

RICHARD NEUMANN,
WALTHER REINHARDH.

It is hereby certified that in Letters Patent No. 1,172,272, granted February 22, 1916, upon the application of Joseph W. Gamble, of Philadelphia, Pennsylvania, for an improvement in "Valves," an error appears in the printed specification requiring correction as follows: Page 3, lines 79-80, claim 3, for the word "casting" read *casing*; and that the said Letters Patent should be read with this correction therein that the same may conform to the record of the case in the Patent Office.

Signed and sealed this 14th day of March, A. D., 1916.

[SEAL.]
